Patented Jan. 2, 1917.

UNITED STATES PATENT OFFICE.

HERMANN F. SCHUBERT, OF VICTORIA, TEXAS.

WELL-DRILLING TOOL.

1,210,704.

Specification of Letters Patent. Patented Jan. 2, 1917.

Application filed September 23, 1916. Serial No. 121,816.

To all whom it may concern:

Be it known that I, HERMANN F. SCHUBERT, a citizen of the United States, and resident of Victoria, in the county of Victoria and State of Texas, have invented certain new and useful Improvements in Well-Drilling Tools, of which the following is a specification.

The present invention relates to well drilling tools and has particular reference to new and useful improvements in tools of this class for boring Artesian wells and the like, automatic means being associated with the drill for engaging the material excavated to withdraw the same from the bore.

An object of my invention is to provide a novel and simple drilling device which is collapsible to engage the material excavated and withdraw the same from the bore.

Another object of my invention is to provide a drill of the class described which may be applied to any of the standard types of drilling machines wherein the vertical reciprocation method is employed.

A further object of my invention is to provide a drill of the class described which is simple in construction, strong and durable, cheap to manufacture and install and effective in operation.

Other objects and advantages to be derived from the use of my improved well drilling tool will appear from the following detail description and the claims, taken with an inspection of the accompanying drawing, in which:

Figure 1 is a perspective view of a well drilling tool embodying the improvements of my invention; Fig. 2 is a vertical sectional view of the same; Fig. 3 is an enlarged detached perspective view of the jaw spreading member; and Fig. 4 is a detailed transverse sectional view of one of the jaws showing the manner of connecting a return spring thereto.

Referring more particularly to the drawing, wherein similar characters of reference designate like and corresponding parts throughout the various views, 10 designates a drill rod, said drill rod having an enlargement 12 on the lower end thereof, said enlargement being formed with a recess 13 and a threaded opening 14, said opening communicating with said recess as best shown in Fig. 2. I provide a jaw carrying rod 15 having a threaded portion 16 for engagement with the threaded opening 14, said rod

being offset as at 17 and formed with a tongue 18 to which is riveted or otherwise secured a jaw 19, said jaw being tapering in longitudinal configuration and semi-circular in cross section. A second jaw 20 is provided substantially identical with the jaw 19 in contour, said jaw 20 being yieldably connected to the rod 15 by means of a flat spring element 21, said flat spring element 65 being riveted to said rod and said jaw. The marginal edges of the jaw 20 are overlapped by the marginal edges of the jaw 19 as indicated at 22. I provide means for spreading the jaws 19 and 20, said means including 70 an arm 23 pivoted at 24 to the jaw 19. The free end of the arm 23 carries a transverse pin 23', on which is mounted an anti-friction roller 25 to engage the inner surface of the jaw 20. An actuating rod 26 formed of 75 a strand of heavy wire is connected at 27 to the pin 23', said rod being formed with an off-set hook portion 28 to which one end of a coil spring 29 is connected. The lower end of the coil spring 29 is connected at 30 80 to a pin 31 permanently carried by the jaw 19. The upper free end of the rod 26 is laterally bent as at 32 and formed with a loop 33, said loop embracing the drill rod 10, a wear compensating washer 34 being disposed beneath the loop 33 and above the enlargement 12 to insure free even rotation of the drill rod.

In use the drill rod 10 is rotated to raise or lower the rod 26, the latter in turn oscillating the arm 23 to bring the roller 25 into or out of engagement with the inner surface of the jaw 20 tending to force said jaw away from or permit the same to move toward the jaw 19. The drill is preferably inserted into 95 the bore with the jaws open and a slight turn given to the same in order to loosen the material to be excavated. The drill rod is now rotated to permit the jaws to collapse whereupon the material located between said 100 jaws will be firmly gripped and may be easily withdrawn from the bore.

I desire to lay particular stress upon the extreme simplicity of my improved drilling tool as well as the facility with which the same may be manipulated, also the reduced cost at which the same may be manufactured and the economic manner in which the same is to be used.

From the above description taken in connection with the accompanying drawing, it is thought that a clear and comprehensive

5 understanding of the construction, operation and advantages of my invention may be had, and while I have shown and described the device as embodying a specific structure, I desire that it be understood that such 10 changes may be made in said structure as do not depart from the spirit and scope of the invention as claimed.

Having thus fully described my invention, what I claim as new and desire to set 15 cure by Letters Patent, is:—

1. A device as specified, including a drill rod having an enlargement on one free end thereof, a second rod adjustably associated with the drill rod, a rigid jaw carried by 20 said second rod, a second jaw yieldably carried by said second rod, and means interposed between said jaws and connected with said drill rod to separate the jaws, at times.

2. A device as specified, including a drill 25 rod having an enlargement on one end thereof, said enlargement being provided with a threaded bore, a second rod having a threaded portion engageable with said bore, a jaw carried by the lower free end of said second rod, a second jaw yieldably associated 30 with said second rod, an actuating rod extending from the drill rod to a point between said jaws, and an arm carried by one of the jaws and connected with said actuating 35 rod to spread the jaws when said drill rod and second rod are relatively moved, and a spring member connected with one of the jaws and said actuating rod for the purpose specified.

40 3. A device as specified, including a drill

rod, said drill rod having an enlargement on one end thereof provided with a threaded bore, a second rod threaded to engage said bore, a jaw rigidly carried by the free end of said second rod, a second jaw yieldably 45 carried by said second rod, said first jaw embracing said second jaw to form a tapering tubular container, an actuating mechanism for separating said jaws including a rod connected with the drill rod, an arm 50 pivoted on one of said jaws engaging the opposite jaw, said arm being pivotally connected at the lower end of said actuating rod, and a spring member connected with one of the jaws and said actuating rod for 55 the purpose specified.

4. In a well drilling tool of the class described, the combination of a drill rod having an enlargement on the free end thereof provided with a threaded bore, a second 60 rod threaded to engage in said bore, a rigid jaw carried by the free end of said second rod, a yieldable jaw carried by said second rod to coöperate with said first jaw, an arm pivoted on said first jaw to engage said 65 second jaw for separating the same, an actuating rod connected with said arm and with said drill rod, and spring means connected with one of said jaws and said actuating rod to move said arm when said 70 drill and said second rod are relatively moved whereby to expand or contract said jaws.

In testimony whereof, I affix my signature hereto.

HERMANN F. SCHUBERT.
